UNITED STATES PATENT OFFICE.

CHESTER L. HOOVER, OF WARSAW, INDIANA.

DOLL CRADLE.

Application filed October 17, 1927. Serial No. 226,709.

The device forming the subject matter of this application is a doll cradle, and the invention aims to provide a novel doll cradle, which may be fashioned cheaply out of wood or similar stock, at trifling expense. The invention has for its object, the provision of a novel form of frame, a novel form of body, and novel means for mounting the body on the frame for swinging movement.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in side elevation, a device constructed in accordance with the invention, parts being broken away;

Figure 2 is an end elevation wherein parts are broken away;

Figure 3 is a sectional view showing a part of the base;

Figure 4 is a sectional view showing a part of the base, the cutting plane in Figure 4 being at right angles to the cutting plane in Figure 3.

In carrying out the invention, there is provided a base, including end pieces 1, preferably made of wood, the end pieces 1 being concaved upon their lower edges, as shown at 2, to form feet 3 adapted to rest on a support 4. The end pieces 1 are supplied with sockets 5 which extend transversely through the end pieces 1. In the sockets 5 are mounted the ends of rods 6, preferably made of wood, and of circular cross section, the ends of the rods 6 being held in the sockets 5 by means of securing elements 7, such as nails, driven downwardly into the end pieces 1 and through the rods 6. The base forms part of

a frame, and in the upper surfaces of the 50 end pieces 1, at points near to the extremities thereof, downwardly diverging seats 8 are fashioned. In the seats 8 are mounted the lower ends of upwardly converging bars 9, which form parts of standards, the bars 9 55 preferably made of wood, and of circular cross section. Securing members 10, such as nails, extend into the end pieces 1, transversely, as shown in Figure 4, and engage the lower ends of the bars 9, to hold them in place 60 in the seats 8. The upper ends of the wooden bars 9 are received in downwardly diverging recesses fashioned in cardioid cap blocks 12, which may be made of wood. Pivot elements 14, such as bolts, are mounted in the 65 cap blocks 12. The numeral 16 marks a body, which may be a basket, including a bail 15, made of wood or similar material. The bail 15 is mounted on the pivot elements 14, and, thus, the body 16 is mounted for swinging 70 movement on the frame above-alluded to. The ends of the bail 15 converge, as shown at 17, and the ends of the body 16 are spaced, as at 18, from the bars 9, so that the body 16 75 will not strike the bars 9, when the body is swung, even though the bail 15 may have some resiliency. The bail 15 extends upwardly far enough so that it forms a convenient handle whereby the body 16 may be rocked with the pivot elements 14 as centers 80 of swinging movement.

What is claimed is:—

In a cradle, a frame comprising standards, a body located between the standards, the standards projecting upwardly with respect 85 to the body, a bail attached at its ends to the ends of the body, and pivot elements connecting the bail with the standards, the pivot elements being located between the body and the crown of the bail, the crown of the bail 90 extending upwardly with respect to the standards, to afford, at any point between the standards, a hand grip and a leverage whereby the body may be rocked.

In testimony that I claim the foregoing as 95 my own, I have hereto affixed my signature.

CHESTER L. HOOVER.
